UNITED STATES PATENT OFFICE

136,154

DESIGN FOR A SEWING BASKET

Virgil G. Beauchamp, Chapin, Ill.

Application April 27, 1943, Serial No. 110,056

Term of patent 14 years

To all whom it may concern:

Be it known that I, Virgil G. Beauchamp, a citizen of the United States, residing at Chapin, in the county of Morgan and State of Illinois, have invented a new, original, and ornamental Design for a Sewing Basket, of which the following is a specification, reference being had to the accompanying drawings, forming part thereof.

The dominant features of my design are shown in solid lines of the drawings.

I claim:

The ornamental design for a sewing basket, as shown and described.

VIRGIL G. BEAUCHAMP.
